UNITED STATES PATENT OFFICE

146,948

DESIGN FOR A CARD FILE

Frank H. Saltz, La Crosse, Wis.

Application July 2, 1946, Serial No. 131,283

Term of patent 14 years

(Cl. D74—2)

To all whom it may concern:

Be it known that I, Frank H. Saltz, a citizen of the United States, residing at La Crosse, in the county of La Crosse and State of Wisconsin, have invented a new, original, and ornamental Design for a Card File, of which the following is a specification, reference being had to the accompanying drawing, forming part thereof.

The figure is a perspective view of a card file, showing my new design.

I claim:

The ornamental design for a card file, as shown.
FRANK H. SALTZ.
